Fastener Corporation, Chicago, Ill., a corpora-
tion of Illinois

Application May 11, 1949, Serial No. 92,620

15 Claims. (Cl. 1-49)

1

This invention relates to stapling devices for securing together papers or similar sheet material and is more particularly concerned with a small portable device which incorporates features of construction enabling it to assume the external appearance of a pocket carried fountain pen.

A general object of the invention is to provide a small portable stapling device using staples preferably connected together by cementing, gluing, etc., in strip form which device comprises a staple supply magazine, a clinching anvil and a driving member arranged in closely associated pivoted relation, the anvil and driving member being normally resiliently urged away from opposite sides of the magazine and being movable towards the magazine to permit the driving member to force the end staple in the magazine laterally outwardly of the same into clinching engagement with the anvil.

A further object of the invention is to provide a device of the type described wherein the entire staple driving mechanism is enclosed, when not in use, in telescoping cylindrical barrel and cap members which are constructed to simulate a pocket carried fountain pen, the cap member being removed when it is desired to operate the stapling mechanism.

It is another object of the invention to provide a stapling mechanism comprising a staple supply magazine in combination with anvil and driving members which are of substantially less length than the magazine and which are pivotally connected at one end to an intermediate portion of the magazine whereby a substantial portion of the rearward end of the magazine is enclosed within a cylindrical shaped casing member while the forward end of the magazine and the anvil and driving members are adapted to be enclosed when not in use, within a cooperating cylindrical cap removably associated with the casing member.

It is a further object of the invention to provide in a stapling mechanism of the type described an open top staple magazine and a cooperating staple feed plate having interengaging portions connecting the same in longitudinal sliding relation and being so constructed that the feed plate may be withdrawn into an inoperative position at the rearward end of the magazine and anchored, without removal from the magazine, while a supply of staples is loaded into the forward end of the magazine through the open top of the same.

It is another object of the invention to provide a stapling mechanism of the type described wherein means is provided for manually retract-

2

ing the staples in the magazine to thereby prevent ejection of the end staple from the magazine upon operation of the driving member.

It is a still further object of the invention to provide in a stapling mechanism of the type described, an open top magazine having resilient means for feeding staples successively beneath a driving member, which is operative in a direction transversely of the end of the magazine, to drive the end staple, and a staple retracting member having slideable relation with the top of the staple magazine and having a hook-like forward end for engaging the endmost staple in the magazine, and upon rearward movement thereof, retracting the same from driving position beneath the driving blade against the operation of the resilient feeding means.

It is another object of the invention to provide in a stapling mechanism of the type described, a staple supply magazine which is U-shaped in cross section, in combination with an anvil carrying base member and a driving blade carrying cover member, which are provided with side wall portions engaging in closely fitting relation the upstanding side walls of the staple magazine and being pivotally connected to the same, the adjacent side wall portions being arranged in the same plane.

It is a further object of the invention to provide in a staple mechanism of the type described, an open top generally U-shaped staple carrying magazine, in combination with an anvil carrying bottom member and a driving blade carrying top cover member, which members are provided with side wall portions pivotally connected at one end to each other and to the side walls of the magazine at a point intermediate the ends of the same, with the pivot portions of the respective members positioned in the same plane and interengaging with each other, whereby they are brought into edge abutting relation upon a limited movement toward and away from each other and from the magazine.

It is a still further object of the invention to provide in a stapling mechanism of the type described a staple carrying magazine having a vertical guideway at the forward end thereof which is formed partially by inturned side wall sections terminating short of each other and a cooperating pivoted cover member having a driving blade on the free end thereof which is operative in said guideway and which is provided with a central outwardly offset portion movable in the space between the inturned ends of the magazine side walls.

These and other objects of the invention will be apparent from a consideration of the stapling mechanism which is shown by way of illustration in the accompanying drawings, wherein:

Fig. 1 is a perspective view of a stapling device embodying the principles of the invention, with the cap separated from the barrel portion of the casing;

Fig. 2 is a plan view of the device with the cap removed and the barrel portion of the casing shown in section;

Fig. 3 is a side elevation of the device with the barrel portion of the casing shown in section and with the stapling head in position for driving a staple;

Fig. 4 is an end elevation of the device;

Fig. 5 is a longitudinal cross section taken generally on the line 5—5 of Fig. 2;

Fig. 6 is a view taken generally on the line 6—6 of Fig. 5;

Fig. 7 is a cross section taken on the line 7—7 of Fig. 5;

Fig. 8 is a partially exploded perspective view of the staple supply magazine and associated mechanism;

Fig. 9 is a detail elevation of the stapling head, similar to Fig. 3 but with the members in the position they occupy at the end of the staple driving operation; and

Fig. 10 is a section taken on the line 10—10 of Fig. 9 with the cap indicated in dotted line.

Referring to the drawings, there is illustrated a stapling device incorporating the principles of the invention in which the mechanism is sufficiently small and compact to be housed in a casing so constructed and proportioned that it has the appearance and size of a conventional writing instrument such as a pocket carried fountain pen.

The stapling mechanism 10 is secured in a ferrule or ring member 11 which is preferably formed of a short metal tubular section. The ferrule 11 surrounds an intermediate portion of the mechanism 10 and forms a part of the housing for the same. The one end of the stapling mechanism 10 extends into a tubular casing 12 which is shaped to simulate the appearance of the barrel portion of a fountain pen and which has a screw-threaded connection at 13 with the ferrule 11. The exposed portion of the stapling mechanism 10 constitutes the stapling head and is shown in Fig. 1 in the open position ready for use in the stapling operation. The stapling head may be contracted (Fig. 9) and positioned within the cap member 14 which telescopes over the same and which frictionally engages with the peripheral surface of the ferrule 11 to hold it in connected or closed condition. The cap 14 is provided with a spring clip 15 which is secured on the closed end thereof by a screw 16 for fastening the same to the pocket of the user in the same manner as a pocket carried writing instrument.

The stapling mechanism 10 consists of a staple storing and supply magazine 17, a bottom anvil carrying arm or plate member 18 and a top plunger shell or driving blade carrying cover member 19. The anvil member 18 and the plunger carrying cover member 19 are arranged on opposite sides of the magazine 17 and pivotally connected thereto to form therewith the stapling head which is exposed by removal of the cap 14 when it is desired to use the mechanism for driving a staple.

The staple supply magazine 17 (Figs. 5 to 10)

comprises channel-shaped inner and outer members 20 and 21, both of which are of generally upwardly opening U-shaped cross section. The outer channel member 21 is positioned at the forward end of the inner channel member 20 with its base 22 secured to the base 23 of the inner channel member 20 by means of rivets 24. The outer channel member 21 is substantially less in length and somewhat wider than the inner channel member 20. It is arranged so that its side walls 25 and 26 extend upwardly in parallel spaced relation to the side walls 27 and 28, respectively, of the inner channel member 20 providing therebetween parallel guideways for receiving the downwardly extending legs of the staples indicated at 29.

The bottom or base 23 of the inner channel member 20 is cut away at the forward end to form the end edge 30, leaving end portions 31 and 32 of the side walls 27 and 28 extending forwardly of the same. The base 22 of the outer channel member 21 is cut back and provided with an upstanding tongue 33 which projects upwardly between the side wall extensions 31 and 32 of the inner channel member 20 adjacent the forward edge 30 of the bottom 23 of the same for a purpose which will be described.

The side walls 25 and 26 of the outer channel member 21 are turned inwardly at the forward end to form vertical end walls or flanges 34 and 35 having their terminating edges in opposed spaced relation and forming a vertical slot in the end of the magazine. The inner surfaces of the end flanges 34 and 35 are spaced a sufficient distance from the end portions 31 and 32 of the inner channel walls 27 and 28 to accommodate a single staple and form therewith a vertical guideway through which successive staples are driven downwardly or laterally out of the magazine.

The staples 29 are urged in a forward direction in the magazine by a feed plate 36 which comprises a channel member of a size to be positioned over the walls 27 and 28 of the inner channel member 20 with the side walls 37 and 38 of the same extending downwardly in encompassing relation to the side walls 27 and 28. The walls 37 and 38 are provided with an inwardly directed detent or shoulder formation 39 which is received in the groove 40 provided in the respective side walls 27 and 28 of the channel member 20 to guide the feed plate 36 in its movement along the channel 20 and prevent its removal in a vertical direction. The feed plate 36 is provided at its rearward end with a reversely bent tongue 41 to which is secured one end of a tension spring 42. The other end of the tension spring 42 is secured to the upstanding tongue 33 at the forward end of the outer channel member 21. The feed plate 36 is relatively short and may be retracted to permit loading of the magazine from the top with a fresh supply of staples.

The plate 36 may be held in retracted position by placing its forward edges in abutting relation with the shoulders 43 which are formed by recessing the top edges of the walls 27 and 28 adjacent the rearward end of the channel member 20. The groove 40 is offset at 44 to accommodate the detent 39 in the retracted position.

A staple retracting plate 45 (Fig. 8) is arranged for limited sliding movement on the forward end of the magazine 17 to permit the staples to be moved toward the rear of the magazine a sufficient distance to withdraw the end staple from driving position. The staple retracting plate 45 engages over the tops of the staples in the maga-

zine with its side edges extending into recesses 46 provided in the top edges of the side walls 25 and 26 of the outer channel member 21. The portions of the side edges of the retracting plate 45 which extend into recesses 46 are somewhat less in length than the length of the recesses to permit relative movement. At the forward end of the recesses 46 rearwardly extending overhanging wall portions 47 are provided to prevent upward movement of the retracting plate 45. Spaced a short distance rearwardly thereof upstanding lug formations 48 are provided which extend into relatively short slots 49 which are provided in the edge portions adjacent the forward end of the retracting plate 45. The lug formations 48 are somewhat less in length than the length of the slots 49 to permit movement of the retracting plate at least a distance sufficient to withdraw the end staple from the driving position. The forward end of the retracting plate 45 is provided with a downturned hook-like tongue 50 which is relatively narrow and which projects into the vertical space between the end walls 34 and 35. The hook 50 extends downwardly a sufficient distance to engage the bight or base portion of the end staple 29. The recesses 46 in the side walls 25 and 26 of the channel member 21 are located sufficiently far above the tops of the side walls 27 and 28 of the channel member 20 to permit sliding movement of the staples between the retracting plate 45 and the side walls 27 and 28.

The retracting plate 45 is provided with an upstanding pin 51 adjacent its rearward end by means of which it may be manually moved in a rearward direction to retract the staples in the magazine by engagement of the hook 50 with the end staples. The retracting plate 45 is provided with a rearward extension 52 which projects within the ferrule 11 when the magazine is assembled with the casing and holds the rearward end of the same in position in sliding relation with the channel member 21. The retracting plate 45 is provided at its forward end with an elongate aperture 53 so that the supply of staples in the magazine will be visible to the user.

The ferrule 11 is provided with an internal recess 54 which is generally rectangular in cross section and of sufficient size to receive in tight fitting relation the magazine 17. The bottom 22 and side walls 25 and 26 of the outer channel member 21 extend into the aperture 54 and dimples 54' are provided on the side walls 25 and 26 which snap into holding relation with the inner marginal edges of the aperture 54 in the ferrule 11 when the ferrule is forced over the rearward end of the channel member 21 (Fig. 2). A set screw 55 (Figs. 1 and 9) may be provided in the ferrule 11 for rigidly securing the ferrule on the magazine 17.

The casing member 12 is provided with an internal chamber forming bore 56 which terminates at the rearward end in an abutment 57 for engagement by the rearward end 58 of the channel member 20 to limit the movement of the ferrule 11 relative to the magazine 17 and to properly position the same for securing by the set screw 55.

The anvil carrying arm 18 comprises a spring metal plate-like member having an end portion 70 provided with transversely extending shallow recesses 59 for clinching the legs of the staples. The member 18 is provided adjacent its rearward end with parallel upstanding side wall formations 60 and 61 and trunnion formations 62 and 63.

which extend somewhat above the side walls 60 and 61 and which are apertured to receive pivot forming pins 64 and 65. The side wall formations 60 and 61 and the trunnion formations 62 and 63 on the respective sides of the member 18 are in the same plane, and embrace in close fitting relation the side walls 25 and 26 of the magazine outer channel member 21. The pivot pins 64 and 65 are secured in apertures 66 in the respective side walls 25 and 26 of the outer channel member 21 to pivotally support the anvil arm 18 beneath the magazine 17 with the forward end extending beneath the vertical staple driving guideway and the clinching recesses 59 aligned with the guideway. The side wall formations 60 and 61 and the trunnion formations 62 and 63, respectively, are separated from each other by inclined slots or recesses 67 and 68. The member 18 is normally urged in a direction away from the magazine 17 by a small leaf spring 69 which extends into the aperture 54 of the ferrule 11 and which is held in position by a tongue 70 projecting downwardly from the bottom 22 of the magazine outer channel member 21 and extending through an aperture 71 in the spring 69.

The plunger shell 19 is channel-shaped in cross section and forms a cover member for the forward end of the magazine 17 with the side walls 72 and 73 (Figs. 5 and 8) projecting downwardly in close fitting relation over the side walls 25 and 26 of the magazine outer channel member 21. At the rearward end the side walls 72 and 73 of the cover member 19 are recessed at 74 and 75 to accommodate the upstanding wall formations 60 and 61 on the anvil member 18. The side walls 72 and 73 are also provided at the rearward end with generally downwardly opening circular slots 76 and 77 in which the trunnion formations 62 and 63 on the anvil member 18 are received to pivotally mount the cover member 19 on the trunnion formations 62 and 63. The portions of the side walls 72 and 73 defining the bottom edges of recesses 74 and 75 engage with the opposed top portions of the side walls 60 and 61 of the anvil carrying member 18 upon closing movement of the cover member 19 to limit the movement of the same towards the magazine 17. The top portion 78 of the cover 19 is provided with a rearwardly opening slot 79 at its rear end to accommodate the pin 51 projecting upwardly from the staple retracting plate 45 and to permit movement of the retracting plate 45 longitudinally of the magazine 17. One or both of the cover side walls 72 and 73 are provided with an inturned lug formation 80 at the forward end of the recesses 74 and 75 for engagement in a vertical slot 81 provided in the adjacent side wall of the outer channel member 21 which provides an interlocking connection between the cover member 19 and the magazine 17, limiting their relative movement away from each other and retaining the same in assembled relation. The lug formation 80 may be sprung out of the slot 81 for disassembly by means of a suitable pointed tool.

The cover member 19 is shaped at the forward end to provide a driving blade formation 82. The driving blade or plunger 82 is preferably formed by turning the forward end of the top wall 78 downwardly and shaping the downturned portion to provide an outwardly offset central rib formation 83 and side or end blade formations 84 and 85. The rib-like offset portion 83 rides in the space between the end members 34 and 35 of the outer channel member 21 and prevents any lateral stress being transmitted to the pivot

by movement of the plunger 82 in the staple driving operation. The plunger 82 is separated at the sides from the side walls 72 and 73 and the latter extend some distance beyond the forward face of the magazine 17 to give added protection to the plunger. The hook-like portion 50 of the staple retracting plate 45 projects into the inwardly opening recess formed by the rib 83 of the driving blade formation 82, when the plate 45 is in its forward position, permitting the foremost staple to be engaged by the blade formations 84 and 85 for the driving operation.

The cover member 19 is provided with an elongate aperture 86 at its forward end which is in general alignment with the aperture 53 in the forward end of the staple retracting plate 45 to permit the user to observe the supply of staples and also to permit the removal of a jammed staple, if necessary, during the operation of the device, without disassembly of the parts.

The cover member 19 is normally urged upwardly away from the magazine 17 by a small leaf spring 87 which may be conveniently secured to the top of the staple retracting plate 45 by the operating pin 51.

The top wall 18 of the cover member 19 is rounded where it merges with the side walls 72 and 73 to conform to the inside contour of the cover member 14 when the latter is placed over the stapling head (Fig. 10).

In using the device for a stapling operation the cap 14 is removed as shown in Figs. 1 to 5 and 9 allowing the plunger shell 19 and the anvil carrying member 18 to move outwardly away from the magazine 17 to the limit of their movement. The paper or other material 88 (Fig. 9) to be stapled is positioned between the anvil member 18 and the magazine 17 while the stapling head is gripped by the user, with the fingers engaging the cover member 19 and anvil member 18. The members 19 and 18 are then pressed towards the magazine 17 to move the driving blade 82 through the vertical guideway at the forward end of the stapling head and to drive the endmost staple 29.

When it is desired to replace the cap 14 on the stapling head the pin 51 is manually retracted to withdraw the endmost staple from the driving position and the cover member 19 and anvil member 18 are moved into closed position relative to the magazine 17 and held there while the cap 14 is positioned over the same and frictionally engaged with the ferrule 11.

When the supply of staples is exhausted a fresh supply may be placed in the magazine 17 by removing the barrel 12 of the casing and retracting the feed plate 36 to expose the top of the magazine. If desired the feed plate 36 may be held in retracted position by engaging the forward end of the same with the abutments 43 while the desired supply of staples is loaded into the magazine through the open top of the same.

While particular materials and specific details of construction have been referred to in describing the illustrated form of the device, it will be understood that other materials and other details of construction may be restored to within the spirit of the invention.

I claim:

1. A stapling device comprising a long channel-like staple supply magazine having a transversely extending staple driving guideway at the forward end thereof and means for delivering successive staples into driving position in said

guideway, a short plate member having means for pivotally mounting the same at one end on the outer faces of the side walls of said magazine with the free end extending on one side of said guideway and forming a staple clinching anvil, a short channel-shaped member having the side walls thereof pivotally mounted at one end on the outer faces of the side walls of said magazine and having a driving blade on the free end thereof in alignment with said guideway, said members being pivoted to the side walls of said supply magazine intermediate the ends thereof for swinging movement about a common axis and said driving blade being operable in said guideway for driving a staple toward said anvil, a ferrule detachably secured in encompassing relation with said magazine adjacent the pivotal connection of said anvil plate and blade carrying members, a tubular section enclosing the rearward end of said magazine and having its end detachably secured to said ferrule, and a removable tubular cap forming section enclosing the forward end of said magazine.

2. In a stapling device comprising a magazine and cooperating anvil and driving blade carrying members, said magazine having an inner member of generally U-shaped cross section with a portion of the bottom cut away at the forward end thereof and having an outer member of generally U-shaped cross section, said inner and outer members being secured to each other with their upstanding walls in spaced relation to form a longitudinal guideway for a supply of staples, said outer member having inwardly directed flanges on the forward end of the side walls thereof in spaced relation to the forward ends of the side walls of the inner member and forming therewith a transversely extending guideway for receiving a single staple, the bottom of said outer member being cut away at the forward end and provided with an upstanding tongue projecting above the bottom of said inner member, a staple feed plate slideable on the open top of said inner member having downwardly directed side wall portions positioned in said longitudinal guideway, a downwardly directed tongue on the rearward end of said feed plate, and a tension spring having opposite ends secured to the upstanding tongue on the magazine member and to the tongue on the feed plate, respectively, for urging the feed plate forwardly to feed successive staples into said transversely extending guideway.

3. In a stapling device comprising a magazine and cooperating anvil and driving blade members, said magazine having upwardly opening inner and outer channel members, said channel members being secured to each other with the side walls thereof in spaced relation to form a longitudinal guideway therebetween for a supply of staples, said outer channel member having flanges extending inwardly on the forward end thereof in spaced relation to the forward ends of the side walls of the inner channel member to form a transverse guideway for receiving said driving blade and a single staple in driving position beneath the same, a staple feed plate slideable on the open top of said inner channel member, and a tension spring secured at opposite ends to the forward end of the magazine outer channel member and to the feed plate to urge the feed plate forwardly for feeding successive staples into driving position in said transverse guideway.

4. A stapling device comprising a magazine

having an inner upwardly opening channel member with a portion of the bottom thereof cut away at the forward end and an outer upwardly opening member also having a portion of the bottom thereof cut away at the forward end secured to said inner member, said members having upstanding wall formations in spaced relation to form a longitudinal guideway for a supply of staples, said outer member having inwardly turned flanges on the forward end thereof in spaced relation to the forward ends of the upstanding wall formations on the inner member and forming therewith a transverse guideway for accommodating a single staple, a tongue on the forward end of said outer member projecting upwardly through the cut away bottom portion of said inner member, a staple feed plate slidable on the open top of said inner member, a downwardly directed tongue on the rearward end of said feed plate, and a tension spring secured at opposite ends to said tongues.

5. A stapling device comprising a magazine having inner and outer upwardly opening channel members, said channel members being secured to each other with upstanding wall portions thereof in spaced relation to form a longitudinal guideway for a supply of staples, said outer channel member having inwardly directed flanges on the forward end thereof in longitudinal spaced relation to the forward ends of the upstanding wall portions of the inner channel member to form therewith a transverse guideway for accommodating a single staple, a staple feed plate slidable on the open top of said inner channel member with downwardly directed wall formations positioned in said longitudinal guideway, and a tension spring secured at opposite ends to the forward end of the magazine and to the feed plate, said feed plate wall formations and said inner channel member wall portions having interengaging detent and recess means for retaining said feed plate in longitudinal sliding relation on said channel member.

6. A stapling device as recited in claim 5 wherein in said detent and recess means comprises an inwardly directed longitudinal rib formation on one of said feed plate wall formations and a co-operating longitudinal groove formation on the adjacent inner channel member wall portion.

7. A stapling device as recited in claim 5 and abutment formations on the top edges of the wall portions of said inner channel member adjacent the rearward end thereof for engagement by said staple feed plate whereby said feed plate may be held in retracted position against the operation of said tension spring while a supply of staples is positioned in the magazine.

8. A stapling device comprising a magazine having means therein for delivering staples successively to the forward end thereof, said magazine having means forming a transverse guideway at said forward end thereof, a plate-like member having an anvil forming portion extending beneath said guideway at one side of said magazine, said plate-like member having upstanding side wall elements longitudinally spaced from said anvil forming portion, said side wall elements being positioned closely adjacent the side walls of said magazine and being pivotally connected thereto and a cover member having a driving blade operable in said transverse guideway to drive successive staples against said anvil, said cover member having depending side wall elements positioned closely adjacent the side walls of said magazine and being pivotally engaged

with the side wall elements of said plate-like member.

9. A stapling device as recited in claim 8 wherein said side wall elements on the sides of said plate-like member and said cover member are positioned in the same planes on corresponding sides of the magazine.

10. A stapling device comprising a magazine having means therein for delivering staples successively to the forward end thereof, said magazine having generally parallel transversely spaced vertical side walls, a bottom plate member having an anvil portion extending beneath the forward end of said magazine, said bottom plate having transversely spaced upstanding side wall elements positioned closely adjacent the vertical side walls of said magazine and pivotally connected thereto and a top cover member having a driving blade operable in the forward end of said magazine to drive successive staples against said anvil, said cover member having transversely spaced side walls positioned closely adjacent the vertical side walls of said magazine and pivotally connected to the same, said side walls on said bottom plate and top cover members being engaged with each other and pivotally movable about a common axis and in the same planes on opposite sides of said magazine.

11. A stapling device comprising a magazine having means therein for delivering staples successively to the forward end thereof, said magazine having generally parallel transversely spaced side walls, a bottom plate member having an anvil portion extending beneath the forward end of said magazine, said bottom plate having transversely spaced upstanding side wall elements positioned closely adjacent the vertical side walls of said magazine and pivotally connected thereto and a top cover member having a driving blade operable in the forward end of said magazine to drive successive staples against said anvil, said cover member having depending side wall portions positioned closely adjacent the side walls of said magazine, the upstanding side wall elements of said bottom plate having circular bearing portions and the depending side wall portions of said cover member having circular apertures for receiving said bearing portions to provide a pivotal connection therebetween.

12. A stapling device comprising a magazine having a guideway at the forward end thereof, an anvil member having a pivotal connection with said magazine and extending beneath said guideway, a cover member on the side of said magazine, opposite said anvil member, said cover member having a pivotal connection with said magazine and having a driving blade operable in said guideway to drive a staple against said anvil, feed means in said magazine for resiliently urging successive staples into said guideway, means in said magazine for retracting the staples against the operation of said feed means, and a tube-like casing having a barrel portion enclosing the rearward end of said magazine and extending adjacent the pivotal connection with said cover member, said casing having a removable cap portion adapted to be telescoped over the forward end of said magazine and to hold said anvil and cover members in non-operative closely associated relation with said magazine, said casing portions being so constructed that they simulate the appearance of a pocket carried fountain pen.

13. A stapling device comprising a magazine having a staple driving guideway at the forward end thereof, an anvil member having a pivotal connection with said magazine and extending

beneath said guideway, a cover member having a pivotal connection with said magazine and provided with a driving blade operable in said guideway to drive a staple against said anvil, staple feed means in said magazine for resiliently urging successive staples into driving position in said guideway, and means for retracting the staples in the forward end of said magazine to prevent the driving of the end staple upon driving movement of said driving blade.

14. A stapling device comprising a magazine having a staple driving guideway at the forward end thereof, an anvil member extending beneath said guideway, a cover member having a pivotal connection with said magazine and provided with a driving blade operable in said guideway to drive a staple against said anvil, a staple feed means in said magazine for resiliently urging the staples toward said guideway, and a manually slidable staple retracting plate in said magazine having a depending hook-like member at the forward end of said magazine for engagement with the endmost staple whereby said staples may be moved out of driving relation with said driving blade.

15. A stapling device comprising a magazine having a guideway at the forward end thereof, an anvil member having a pivotal connection with said magazine and extending beneath said guideway, a cover member at the opposite side of said magazine having a pivotal connection with said anvil member, said cover member having a driving blade operable in said guideway to drive a
